PHONOGRAPH PICKUP ARM

Robert Louis Deschamps, West Chicago, Ill., assignor to Shure Brothers, Incorporated, Evanston, Ill., a corporation of Illinois

Filed May 6, 1960, Ser. No. 60,476

Term of patent 14 years

(Cl. D26—14)

*Fig. 3.Fig. 5Fig. 4*Fig. 1 is a side elevational view of a phonograph pickup arm, showing my new design;

Fig. 2 is a top plan view;

Fig. 3 is a fragmentary rear elevational view, partly in cross-section taken on line 3-3 in Fig. 1;

Fig. 4 is a fragmentary front elevational view as viewed along line 4-4 between the arrows in Fig. 2; and

Fig. 5 is a fragmentary bottom plan view thereof, as viewed along a line 5-5 in Fig. 1 between the arrows.

I claim:

The ornamental design for a phonograph pickup arm, substantially as shown.
